[57] **CLAIM**

The ornamental design for a cleaning implement mounting surface, as shown and described.

DESCRIPTION

FIG. 1 is a perspective view of a cleaning implement mounting surface, embodying my new design;

FIG. 2 is a side elevational view thereof, the opposite side elevational view thereof being a mirror image;

FIG. 3 is a top view thereof;

FIG. 4 is a bottom view thereof;

FIG. 5 is a front elevational view thereof; and,

FIG. 6 is a rear elevational view thereof.
